UNITED STATES PATENT OFFICE.

JOHN MARSHALL DOBIE, OF ALEXANDRIA, VIRGINIA.

DESIGN FOR EARRING PENDANT.

Application filed February 5, 1924. Serial No. 8,535. Term of patent 3½ years.

To all whom it may concern:

Be it known that I, JOHN MARSHALL DOBIE, a citizen of the United States, residing at Alexandria, in the State of Virginia, have invented a new, original, and ornamental Design for Earring-Pendant, of which the following is a specification, reference being had to the accompanying drawings, forming part thereof.

Figure 1 is an elevation showing one face of the pendant.

Figure 2 is an elevation showing another face of the pendant.

Figure 3 is an elevation showing the third face of the pendant, and

Figure 4 is a bottom plan view of the pendant.

I claim:

The ornamental design for earring-pendant as shown.

JOHN MARSHALL DOBIE.
